U.S. Appl. No. 29/587,373, filed Dec. 13, 2016, Meiji Kitamura. Office Action dated Mar. 22, 2018 in Design U.S. Appl. No. 29/587,373.

Primary Examiner — John Windmuller*Assistant Examiner* — Benjamin M Weeks(74) *Attorney, Agent, or Firm* — Drinker Biddle & Reath LLP(57) **CLAIM**

I claim the ornamental design for an electronic musical instrument, as shown and described.

DESCRIPTION

FIG. 1 is a perspective view of an electronic musical instrument showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged partial rear view taken at line 8-8 of FIG. 2.
